UNITED STATES PATENT OFFICE.

WILLIAM F. CHESTER, OF NEW YORK, N. Y.

ELECTRIC BURGLAR-ALARM ATTACHMENT FOR AUTOMATIC SIGNALING APPARATUS.

SPECIFICATION forming part of Letters Patent No. 280,578, dated July 3, 1883.

Application filed March 24, 1883. (No model.)

To all whom it may concern:

Be it known that I, WM. F. CHESTER, of New York, in the county of New York and State of New York, have invented a new and Improved Electric Burglar-Alarm Attachment for Automatic Signaling Apparatus; and I do hereby declare the following to be a full, clear, and exact description of the same, reference being had to the accompanying drawings, forming part of this specification, and to the figures and letters of reference marked thereon.

My invention has for its object, primarily, to extend the usefulness of the district-messenger system now in such extensive operation in the principal cities of this and other countries by combining with the automatic signaling mechanism employed in such system at each station or call-box a normally-open local circuit, including a battery and an electro-magnet, extending throughout a building or other place, to be protected and arranged so as to be closed by the opening of a window, door, or blind, or by the unwarranted interference with or trespassing upon any part of the building or place to be protected, and the electromagnet included in said circuit being adapted, upon the closure of the circuit, to actuate the tripping device of the signaling mechanism and set the latter in operation to turn in a signal at the central office; and it further has for its object the provision of means whereby upon the signaling mechanism being set in operation the local circuit will be automatically opened, so as to prevent wastage of the local battery.

The novel features of my invention will be first described, and then pointed out particularly in the claims at the end of this specification.

Referring to the accompanying drawings, Figure 1 represents a front elevation of a district call-box containing an automatic signaling mechanism and showing the application of my improvements thereto. Fig. 2 is a sectional view taken on the line *x x*, Fig. 1. Fig. 3 is a sectional view taken on the line *y y*, Fig. 1; and Fig. 4, a detail view, showing the gearing of the signaling mechanism.

Similar letters of reference in the several figures denote the same parts.

The letter A indicates a metal call-box, containing the signaling mechanism and other operative parts.

B represents the main actuating-shaft of the signaling mechanism, upon which is mounted a disk or drum, C, having a peripheral tooth or projection, *a*, and a peripheral recess or notch, *b*, and upon which is also mounted a volute spring, D, and a gear-wheel, E, one end of said spring being connected to the shaft and the other end to a stationary part at *c*, and the connection between the shaft and the gear E being effected by means of a ratchet and pawl, (not shown,) so that when the gear E is held from rotation, as hereinafter described, the spring 55 can be wound up by the application of a key or crank to the outer end of the shaft D, and when, on the other hand, the wheel E is released, the spring will rotate the shaft and the disk C thereon in the direction indicated by the arrow, 60 Fig. 1. The gear E meshes with a pinion, F, on a shaft, F, which shaft also carries a circuit-breaking disk, G, at its outer end, and a gear-wheel, F', which meshes with a pinion, H', on a third shaft, H, that also bears an es- 65 capement-pinion, H'', with which engages an ordinary escapement, I. This arrangement of gearing is such as is commonly employed in devices of this character, the object desired to be accomplished by it being the gradual ro- 70 tation of the shaft B and its disk C, as well as the gradual rotation of the circuit-breaking disk G on the shaft F, when the unwinding of the spring is permitted to take place, as will 75 presently be explained. 85

G' is a tripping-lever, pivoted at *g* and having its upper arm, G², extending upward and adapted to be normally projected into the recess or notch *b* in the rim *b'* of the disk C, and having projecting from its lower arm, G³, below its pivot, a stud, G⁴. A spiral spring, G⁵, operates to pull the lower arm of the lever forward and to keep the stud G⁴ in the path of a stud, G⁶, projecting from the side of the disk G. When the mechanism is wound up by the 90 rotation of the shaft B, as aforesaid, the end of the upper arm, G², of the lever stands projected through the recess or slot in the rim of the drum C, while the stud G⁴ on the lower arm of the lever rests under the stud G⁶ on the 95 disk G, thus preventing the rotation of said disk G, and consequently the rotation of the 100 whole train of connected gearing. When, however, the lower arm, G³, is from any cause swung outward, the end of the upper arm will 105 be withdrawn from the slot or recess in the

rim of disk C, and the stud G⁴ will release the stud G⁶ and allow the train of gearing to be set in motion. As the disk C revolves the end of the upper arm of the lever will bear against 5 the under side of the rim of said drum, and there remain and slide in contact until the slot or recess in the rim again comes opposite, whereupon the spiral spring G⁵ will pull the lower arm of the lever forward, thereby causing 10 the end of the upper arm to pass up into such slot or recess, and the stud G⁴ to again move into the path of the stud G⁶ and stop the further motion of the mechanism.

J is a metal finger supported on an insulating-block, K, and adapted to bear lightly upon the periphery of the disk G. The main signaling-circuit (which is a normally-closed one) comes in at binding-post 1, passes up wire 2 to the metal finger J, thence to disk G, thence 15 through the connected metal parts of the mechanism to the metal casing A, and thence out at terminal or binding post 3, connected to the metal case. It is obvious, therefore, that when the drum G is rotated the main-line circuit will 20 be broken and made as many times as there are notches in said disk, for as the metal finger reaches each notch its point will drop down into said notch and cause a break of the circuit, while upon the engagement of the spring 25 with the disk beyond said notch the circuit will be re-established, and so on, the makes and breaks being repeated until the spring 30 finally rests upon and in electrical contact with the smooth unbroken portion of the periphery 35 of the disk.

N and O represent two metal spring-arms mounted upon an insulating-block, P, and having a tendency to spring apart at their free ends, so as to keep out of contact with each 40 other. From spring N extends a wire, 4, to an insulated binding-post, 5, and from the spring-arm O extends a wire, 6, through the helices 7 8 of an electro-magnet, 9, to another insulated binding-post, 10.

45 11 represents a short metal arm, bearing a stud, 12, of insulating material, and pivoted at 13, being limited in its motion on one side by a stop, 14, and on the other side by a stop, 15. The end of arm 11 projects in the path 50 of the projection or tooth a on the disk C of the signaling mechanism, and when the signaling mechanism is wound up the said tooth a strikes said arm and swings it against its stop 14, as shown in Fig. 1, and causes the 55 insulating-stud 12 to press the metal fingers N O in contact with each other; but as soon as the signaling mechanism is tripped and the disk C started back, the arm 11 gradually falls back to its stop 15, and the metal springs N 60 and O spring apart again out of contact. The local protecting-circuit 16 is connected to the binding-posts 5 and 10, and includes a battery, 17, and any number of contact-making devices—such as 18 and 19—applied to doors, windows, blinds, &c., of the building or other place to be protected. The continuation of 65 the local circuit through the instrument has

already been indicated as extending from binding-post 5, through wire 4, to spring-arm N, to spring-arm O, to wire 6, through the helices 70 of the electro-magnet 9, and thence back again to binding-post 10.

In front of the poles of the electro-magnet 9 is an armature, 20, which is secured to the lower end of a pivoted lever, 21, whose upper end 75 overlaps the lower end of the tripping-lever G', though normally held away from the same by the tension of a suitable spring, 22.

All the parts of the apparatus having been now described, its operation will be readily 80 understood. When the apparatus is set for operation, the parts are in the position shown in Fig. 1, the signaling mechanism being wound up and held in check by the tripping-lever G', and the spring-arms N O in the local 85 circuit being held in contact. When, now, the local circuit is closed, by the bringing together of the contacts 18 and 19, for instance, the cores of the electro-magnet 9 will be magnetized and will attract their armature 20, 90 thus causing the lever 21 to rock the tripping-lever G' and set the signaling mechanism into operation to turn in a signal at the central office. As the disk C of the signaling mechanism rotates, its tooth a releases the short pivoted arm 11, and the latter drops down upon its lower stop or stud, 15, thus releasing the spring-arm O from contact with the arm N and opening the local circuit. From this it will be seen that the closing of the local circuit 100 by a burglar, or from any other cause, will send a call for assistance to the central office, and as soon as the signaling apparatus has been set in motion it will automatically open the local circuit again, and thus prevent wastage 105 of the local battery.

Having thus described my invention, I claim as new—

1. The combination, with an automatic signaling mechanism and a tripping device for holding the same in check, of a local protecting-circuit, including a battery and an electro-magnet for releasing the tripping device upon the closing of the local circuit, and means operated by the signaling mechanism for automatically opening the local circuit again to prevent wastage of the local battery, substantially as described. 110

2. The combination, with an automatic signaling mechanism and a tripping device for holding the same in check, of the local protecting-circuit, including the battery and the electro-magnet for releasing the tripping device upon the closure of the local circuit, the spring-arms in the local circuit, the pivoted 115 lever normally holding the said spring-arms together, and the tooth on the disk of the signaling mechanism operating upon the pivoted lever, substantially as described. 120

WILLIAM F. CHESTER.
